UNITED STATES PATENT OFFICE

112,000

DESIGN FOR A BURIAL CASKET SHELL

Harry S. Scholl, Chicago, Ill., assignor to F. H. Hill Company, Inc., Cleveland, Ohio, a corporation of Ohio

Application August 13, 1938, Serial No. 79,305

Term of patent 14 years

To all whom it may concern:

Be it known that I, Harry S. Scholl, a citizen of the United States, residing at Chicago, in the county of Cook and State of Illinois, have invented a new, original, and ornamental Design for a Burial Casket Shell, of which the following is a specification, reference being had to the accompanying drawing, forming a part thereof.

Referring to the drawing:

Fig. 1 is a perspective view of a burial casket shell embodying the design;

Fig. 2 is a side elevation of the same; and

Fig. 3 is an end elevation.

I claim:

The ornamental design for a burial casket shell, as shown.

HARRY S. SCHOLL.
